Patented Jan. 6, 1920.

UNITED STATES PATENT OFFICE.

FRANKLIN E. ARNDT, OF GALION, OHIO.

CLAMP FOR BURIAL-VAULTS.

1,327,011.

Specification of Letters Patent.

Patented Jan. 6, 1920.

Application filed June 14, 1919. Serial No. 304,292.

To all whom it may concern:

Be it known that I, FRANKLIN E. ARNDT, a citizen of the United States, residing at Galion, in the county of Crawford and State of Ohio, have invented certain new and useful Improvements in Clamps for Burial-Vaults, of which the following is a specification.

This invention comprehends certain new and useful improvements in locking devices for burial vaults, and comprises generally a plurality of locking devices consisting of bolts inserted through the door of the vault, and clamps having screw-threaded engagement with the bolts and frictionally engaged therewith so that upon an initial movement of the bolts, the clamps will be swung around into locking engagement with the wall of the vault, and then upon a further rotation of the bolts, will be drawn toward the door to lock the door securely in position and at the same time hermetically seal the vault.

One of the objects of the invention is to provide a stop block through which the bolt passes having means thereon which will positively limit the rotation of the clamp to an operative position but which is so formed that it will allow a relatively considerable inward movement of the clamp under the action of the bolt to thus cause the gasket between the door and the bolt to be compressed to its full extent.

A further object is to provide in a construction of the character described a clamp having a head at one end and an arm extending parallel to the bolt on which the clamp is mounted and parallel to the path of movement of the clamp, which arm is adapted to bear against the door of the vault when the bolt has been fully turned up and the clamp has been drawn to its full extent against the plunger on the body of the bolt whereby the clamp will be supported at two points to thereby prevent the clamp from exerting a bending strain on the bolt.

And a further object is to cheapen constructions of this character, and provide a construction which is very simple, in which the parts may be readily assembled, and which does not require to be attached by rivets or other means to the door of the vault itself.

Other objects will appear in the course of the following description.

My invention is illustrated in the accompanying drawings, wherein:

Figure 1 is a fragmentary longitudinal section of a burial vault provided with my improved lock;

Fig. 2 is an inside face view of the lock;

Fig. 3 is a face view of the stop block; and

Fig. 4 is a side elevation of the stop block.

Referring to these drawings, 10 designates the vault body, this vault body being open at one end. Attached to the open end of the vault body on its inner face is an angle iron 11 having an inwardly extending flange 12. Disposed exteriorly of this flange is a gasket 13. The vault door 14, which is of metal, is of a size to fit within the end of the vault. Disposed at a plurality of points around the door 14 are the locking or clamping devices which I will now describe. The door 14 adjacent its margin is formed with a plurality of square or polygonal openings 15. Adapted to rest against the inner face of the door at each one of these openings is a stop block 16, which is approximately segmental in form, and which is provided with a square hub 17 adapted to fit within the opening 15. This square hub has a circular aperture 18 drilled entirely through it. At one corner of the plate forming the stop block 16 is disposed an outwardly extending stop lug 19, and at the other corner is disposed a like lug 20. These lugs have an angular relation to each other of 90°.

Extending through the stop block 16 is a bolt 21 having a head 22 at one end, the shank of this bolt being smooth for a portion of its length from the head and then being screw-threaded, as at 23, and formed with a transverse opening for a cotter pin. Mounted upon the screw-threaded portion 23 of the bolt is a clamp 24, which clamp extends radially in one direction and is formed with a curved head 25. The opposite end of the clamp is formed with an arm 26 which extends parallel to the bolt 23. The distance of the arm 26 from the axis of the bolt is the same as the distance of the stop lugs 19 and 20 from the axis of the central bore 18. Therefore, these stop lugs will be disposed in the path of movement of this arm 26. Disposed between the clamp 24 and the face of the stop plate or block is a coiled compression spring 27.

The operation of this device will be obvious. Before the door 14 is inserted in the

end of the vault, all of the clamps 24 are turned so that the arms 26 bear against the lugs 20. Under these circumstances, the clamps will be turned with their arms in 5 parallel relation to the angle iron 12. The spring 27 will secure sufficient friction between the bolt and the clamp, but when the bolt is turned, the clamp will turn with it. Therefore, all the bolts are rotated initially 10 so as to carry the clamps around with their heads 25 extending over the flange 12. The arms 26 will thus be brought in engagement with the stops 19. A further rotation of each bolt, therefore, cannot rotate the clamp 15 any further but the screw-threads 23 will act upon the clamp to draw the clamp inward, compressing the spring 27. Inasmuch as the lugs 19 and 20 extend outward parallel to the path of movement of the arm 26, it will be obvious that these lugs are 20 relatively long and will permit considerable inward movement of the clamp. As the clamp moves inward it will draw the door against the gasket 13 and cause a compression 25 of this gasket. When the gasket has been compressed to a sufficient degree, the end of the arm 26 will bear against the face of the door, and if the bolt has been slightly bent by the pressure of the head 25 against 30 the flange 12, the bearing of the arm 26 against the face of the door on the further rotation of the bolt will cause the re-straightening of the bolt.

A washer of lead or any other suitable 35 material 28 is disposed around the shank of the bolt between the head 22 and the door, this washer being of such size as to cover the opening through the door, thus making an absolutely tight joint between the head 40 of the bolt and the door.

The advantages of this invention reside, for one thing, in the fact that the parts may be readily assembled and that the stop block does not need to be attached by rivets or 45 any other means to the face of the door. And a further advantage lies in the fact that the load on the bolt is equalized after the gasket has been compressed to a certain degree and as much pressure may be put on 50 the bolt as is required without deforming the bolt. It will further be seen that practically the amount of compression which may be placed upon the gasket is not limited, as the nut is rotated after the arm 55 26 has reached the door, this will cause the clamp to fulcrum on the extremity of this arm and the head 25 to bear with increased force on the flange 12. It will be seen that the fastening means is all inside the vault 60 where it is fully protected. When it is desired to open the vault, the bolts are turned off and this action unscrews the clamp so that it moves outward until the arm 26 escapes from the stop 19 and then a further 65 rotation of the bolt will turn the clamp to

a position where its head is parallel to the flange 12 and released.

It will be understood, of course, that there are a plurality of these bolts disposed around the vault door adjacent the margin thereof 70 equi-distantly, and that all of these bolts grip the flange 12.

While I have illustrated certain details of construction and form, I do not wish to be limited to these, as it is obvious that changes 75 might be made in the details of construction without departing from the spirit of the invention as defined in the appended claims.

I claim:—

1. In combination with two parts to be 80 locked together, a bolt carried by one of said parts, a clamp carried by the bolt and engageable with the other part, said clamp being provided with an arm, a stop lock formed with spaced lugs with which said arm is adapted to engage, said stop block having a non-rotative engagement with the first named part, and a spring interposed between the clamp and stop block and holding the stop block in operative position. 90

2. A vault door, a locking device therefor comprising a bolt having a head and a shank extending through the door, the outer end portion of the shank being screw-threaded, a clamp screw-threaded on the 95 bolt and having a head on one end, and an arm extending parallel to the bolt on the other end, a stop block on the inside of the door and held from rotation, having a pair of stop lugs extending outward from the 100 stop block parallel to the bolt, the stop lugs being disposed in planes in angular relation to each other, the arm on the clamp being adapted to engage one or the other of the stop lugs to prevent a rotation of the clamp 105 with the bolt, said stop lugs permitting a rotation of the clamp through a segment of a circle, and a coiled compression spring bearing at one end against the clamp and at the other against the stop block. 110

3. A vault door having a polygonal opening adjacent its margin, a locking device for the vault door comprising a stop block disposed on the inside of the door and having a polygonal hub engaging in said polygonal 115 opening, the stop block being formed with a pair of lugs projecting outwardly from the door and disposed in planes having angular relation to each other, a bolt passing through the stop block and rotatable therein and having the inner end of its shank screw-threaded, a clamp having screw-threaded engagement with the bolt and having a curved head at one end, and an arm at the other end extending parallel to the axis of the 120 bolt and adapted to abut against one or the other of the stop lugs when the bolt is turned to a quarter of a revolution, and a spring bearing against the stop block and against the clamp. 125

4. The combination with a vault open at one end and having at this end an inwardly extending flange and a gasket upon the outer face of the flange, of a door for closing the open end of the vault having at its margin a polygonal opening, a stop block resting against the inner face of the door and having a polygonal head for the polygonal opening, the stop block being formed with
- 10 two outwardly projecting lugs disposed in planes in angular relation to each other, a bolt having a head at one end passing through the stop block and rotatable therein, the inner end of the shank of the bolt being
- 15 screw-threaded, a clamp through which the screw-threaded portion of the bolt passes and having at one end a head and at its opposite end an arm extending parallel to the axis of the bolt and adapted to engage with
- 20 one or the other of the stop lugs on the stop block when the clamp is turned, a compression spring bearing against the stop block and against the clamp, and a washer disposed between the head of the bolt and the
- 25 doors.
5. In combination with parts to be locked together, one of said parts being formed with a non-circular opening, a stop block formed with a hub corresponding to and receivable in said opening whereby to prevent the rotation of said block, said block being formed with laterally spaced lugs, a bolt carried by said last named part, a clamp carried by the bolt and engageable with the other part, said clamp being provided with an arm extending between said stop lugs and adapted to engage therewith whereby the movement of the clamp is limited in both directions, and an expansion spring encircling said bolt between the stop block and clamp and bearing against the same whereby the spring serves to hold the stop block in engagement with the opening in the first named part.
6. In combination with parts to be locked together, one of said parts being formed with a non-circular opening, a stop block formed with a hub corresponding to and receivable in said opening, said block being formed with lugs extending parallel to the axis of the opening and disposed in angular relation to each other, a bolt passing through the stop block and freely rotatable therein, a clamp carried by the bolt and having a head on one end engageable with the other part and at its other end provided with an arm extending parallel to the bolt and disposed between said stop lugs and adapted to engage therewith whereby the movement of said clamp is limited in both directions, and an expansion spring encircling said bolt between the stop block and clamp and bearing against the same and serving to hold the stop block against detachment from the opening in the first named part.

In testimony whereof I affix my signature.

FRANKLIN E. ARNDT.
